UNITED STATES PATENT OFFICE

93,119

DESIGN FOR AN EMBLEM

Harry L. Magee, Bloomsburg, Pa., assignor to Bloomsburg Flying Club, Bloomsburg, Pa., a corporation of Pennsylvania

Application May 19, 1934, Serial No. 51,849

Term of patent 7 years

To all whom it may concern:

Be it known that I, HARRY L. MAGEE, a citizen of the United States, and a resident of Bloomsburg, Pennsylvania, have invented a new, original, and ornamental Design for an Emblem, of which the following is a specification, reference being had to the accompanying drawing forming part thereof, in which the figure is a face view of an emblem illustrating my new design for an emblem. The emblem has no appreciable thickness.

I claim:—

The ornamental design for an emblem, substantially as shown and described.

HARRY L. MAGEE.
